UNITED STATES PATENT OFFICE.

FREDERICK W. KROEGER, OF ST. HELENA, CALIFORNIA.

SAFETY-RAIL AND REIN-GRIP FOR VEHICLES.

SPECIFICATION forming part of Letters Patent No. 335,288, dated February 2, 1886.

Application filed September 12, 1885. Serial No. 176,969. (No model.)

To all whom it may concern:

Be it known that I, FREDERICK WILLIAM KROEGER, of the town of St. Helena, county of Napa, State of California, have invented an improvement in an Attachment to Vehicles Drawn by Animals; and I hereby declare the following to be a full, clear, and exact description thereof.

My invention consists of a safety-rail, A, of iron or other suitable material, of sufficient thickness to secure the necessary strength, made of one continuous piece without joint, and secured to the body of the vehicle with half-staples and bolts, as shown in the accompanying drawings. The rail A has a loop, B, at the right-hand side. (Shown in the drawings.) Attached to the rail A is a rein grip, check, or holder, C, for purposes hereinafter mentioned. Attached to the rail also, and forming part of the rein-holder, is a thimble, D, made of leather, rubber, or other suitable material. This thimble may be attached in the manner shown or with rivets, or in the shape of a round tube—as, for instance, a section of gutta-percha hose.

Figure 1 is a front view of the apparatus; Fig. 2, a side view, and Fig. 3 is a sectional view.

Fig. 1 shows the loop B, to be partly elevated above the horizontal rail A. Fig. 2 shows the curved brace e, while Figs. 2 and 3 show the manner in which the reins are securely fastened.

In Fig. 1 is shown one of the half-staples 35 wherewith the apparatus is secured to the body of the vehicle.

I will now proceed to explain the purposes of my invention. The safety-rail A is to guard the driver against accidents—such as being 40 drawn over the dashboard by the reins or being thrown under the animal's feet by the front wheels dropping suddenly into a hole, the breaking of an axle, or in case of a runaway, and, in consequence thereof, the vehicle coming into violent collision with some 45 opposing object. I claim that in either case or in any other the safety-rail will enable the

driver to recover himself and retain control over his animals. The loop B is for the purpose of a hand hold to assist in mounting and 50 dismounting the vehicle. The elevated portion of the loop shown in the drawings is a guard to prevent the lines or reins from slipping off the horizontal rail A on the right-hand side. The horizontal rail A will support 55 the weight of the reins, thus rendering the act of holding the reins much less fatiguing than as at present without the attachment. The rein grip or lock acts upon the principle of the lever—the heavier the strain on the reins 60 the firmer the grip. As can be seen at a glance, the reins of one or more animals can be fastened instantly by the driver letting them slide from the horizontal rail A upon the lever C on top, and by a single motion of the hand 65 slipping them under the grip formed by the lower end of the lever C pressing against a projection on the vertical rail A. In like manner the reins can be released instantly. The thimble D is attached to prevent or subdue 70 any noisy rattling of the apparatus; but practical use may prove that it can be dispensed with.

I claim that the rein-grip alone will be a great means of safety and convenience to guard 75 against animals starting during the absence of the driver, and will completely obviate the present clumsy, unsafe, and tedious method of fastening the reins around the whip-socket, dashboard, or other convenient projection 80 which may present itself. To peddlers, butchers, bakers, milkmen, and others of like pursuit it will certainly be a great convenience.

I claim as my invention—

The safety-rail A, with its loop B, and the 85 lever attachment rein grip or lock C, with thimble D, the entire apparatus secured to the body of the vehicle with half-staples and bolts and nuts, as shown and described.

FREDERICK W. KROEGER.
